UNITED STATES PATENT OFFICE

WILLIAM W. LASKER, OF BROOKLYN, NEW YORK, ASSIGNOR, BY MESNE ASSIGNMENTS,
TO REMINGTON RAND INC., OF NEW YORK, N. Y., A CORPORATION OF DELAWARE

CARD PUNCH

Application filed December 18, 1923. Serial No. 681,334.

My invention relates to machines for operating punches, and broadly stated, it comprises punches which are operated from a suitable source of power and keys manipulated by an operator, each of which, when operated, causes the source of power to actuate the punch. My invention is particularly useful for punching holes in cards which are used in tabulating and similar machines. I will describe a machine embodying my invention and then point out the novel features thereof in claims.

In the accompanying drawings, Fig. 1 is a plan view of a machine embodying my invention, and for illustrative purposes shows a machine for punching holes in cards. Fig. 2 is a front elevation of the machine of Fig. 1, except that the keys are in section, the section being taken on the line 2—2 of Fig. 1. Fig. 3 is an end view of the machine, with one key depressed, and taken partly in section, the section being taken on the line 3—3, of Fig. 1. Fig. 4 is a sectional view of the machine of Fig. 1, the section being taken on the line 4—4 of Fig. 1. Figs. 5, 6 and 7 are each detail views showing different positions of the punching and escapement mechanisms.

In the drawings the keys 20 rock on rods 21 and are held up in engagement with the rods 21 by compression springs 22. Extending upwardly from the central portion of each key 20 is a rod 23, the upper ends of which are guided by slots in a plate 23a suitably supported from the framework of the machine. Each rod 23 has extending from one side a shoulder 24 and pivoted to the rod is an arm 25. The free end of each arm 25 is bent so that it will engage with the corresponding shoulder 24 (see Fig. 5) and each arm 25 is normally held in engagement with the shoulder 24 by a spring 26. Extending across the length of the device are a series of bars 27, each of which, at one end, is pivoted to a bell crank lever 28, and near the other end is provided with a cam shoulder 30 which is normally pressed against shoulder 24 by a spring 29. It is to be noted that each arm 25 extends slightly beyond the corresponding shoulder 24 (see Fig. 3), so that the end of each of these arms rests upon a bar 27. As shown in Fig. 3,

if a key 20 is depressed, shoulder 24 corresponding to such key will drop and the shoulder 30 of bar 27 will be drawn in between shoulder 24 and arm 25 by the action of the spring 29. Each bar 27 also carries a projection 31, which, when the bar 27 has moved forward between the shoulder 24 and arm 25 (see Fig. 6) will engage the corresponding tooth group 32.

36 designates a suitable source of power, here shown as being an electric motor, the armature of which drives a shaft 35, carrying a bevel gear 35a which meshes with a bevel gear 34. The bevel gear 34 is fast on a shaft 33 which is suitably mounted in the framework of the machine. The shaft 33 is provided with a plurality of groups of teeth 32, one group being provided for each mechanism through which a punch is operated. When the machine is in operation the groups of teeth are rotating rapidly. As soon as engagement occurs between a projection 31 and a tooth of a group 32, the bar 27 is pushed toward the right. The pressure exerted on bar 27 will cause bell crank lever 28 to oscillate about shaft 37. Pivoted to the other arm of the bell crank lever 28 is a bar 38. A second set of bell crank levers 39 are mounted on shaft 40. Bell crank levers 39 are pivoted to the bar 38 and at their other ends are connected with bars 27 by pins 41 which move in slots 42 in bars 27. As shown in Figs. 5, 6, and 7, a movement of bar 27 to the right, by causing bell crank levers 28 and 39 to oscillate, will move bar 38 toward the back of the machine. Operatively connected with each bar 38 is a plate 43 carrying a pin 44. Each pin 44 is positioned opposite a punch 45 mounted in punch plate 46. It is thus apparent that the backward movement of bar 38 resulting from the depression of the corresponding key 20 will immediately result in the operation of the corresponding punch 45 and cause a hole to be pierced in a card positioned in card rack 47.

In devices of this kind it is ordinarily desirable that the holes punched in the cards be arranged in spaced columns. In order to accomplish this, plates 43 and punch plate 46 are mounted on a movable carriage 48.

Carriage 48 is drawn toward the right hand end of the machine by a flexible strap 49 which passes over pulley 50 and is connected with a spring 50'. Carriage 48 is held in its initial position by a dog 51 which is fixed on shaft 52 and engages with a rack 53. Extending up from dog 51 is a pin 54. An escapement member 55 is fixed on shaft 56 and at one end it engages with pin 54 and has the other end so shaped as to engage with rack 53. When shaft 56 is rotated in a counter-clockwise direction, escapement member 55 will engage with rack 53 and dog 51 will be lifted from the rack, thereby permitting the carriage 48 to advance one tooth space. Fixed on shaft 56 are a series of arms 57 each carrying a pin 58. Each plate 43 carries an extension 59 adapted to engage with a corresponding pin 58; accordingly the normal movement of a key 20 will not only cause a hole to be punched in the card but will result in the carriage being advanced one tooth space. In order that it may be possible to advance the carriage rapidly from one group of indications to another, I provide a special group spacing key 20'. This key, like the others, is connected to a bar 27 which has a plate 43' corresponding with plates 43. It does not, however, engage with any punch corresponding to punches 45. Plate 43' carries an extension corresponding to extensions 59 and likewise carries an additional extension 60 which is adapted to cooperate with pin 61, mounted on arm 62, fixed to shaft 63. A movement of shaft 63 in a counter-clockwise direction will cause dog 51 to become disengaged from rack 53 without permitting escapement member 55 to engage with the rack, so that the carriage will be drawn to the right until trip member 64 engages with a stop 65 which has been fixed in a predetermined position. The connections between shaft 63 and dog 54 follow standard practice in this art, and accordingly the details of such connection are not shown in the drawings. It will be noted (see Fig. 7) that when bar 27 has been pushed to the right by the action of a cam wheel 32, shoulder 30 will pass from between the corresponding shoulder 24 and arm 25. This will permit the corresponding key 20 to assume its original position. As soon as such cam wheel 32 passes from engagement with the projection 31, bar 27 will be drawn back to the left by the action of a spring 66. As the bar 27 is drawn back to the left the cam surface of shoulder 30 will strike against the shoulder 24 and arm 27 will be pushed back clear of cam wheel 32. The return movement of arm 27 will cause bell crank levers 28 and 39 to return to their original positions and carry back with them bar 38. This will release the pressure on the corresponding punch 45 which will be withdrawn from the card by the action of a coiled spring 45a.

In order to assist in setting the machine, it may be provided with a spacing key 20". This key has pivoted to it a link 67, to which in turn is pivoted a lever 68. Attached to lever 68 is shaft 69. Shaft 69 carries arms 70 and 71 between which is mounted a rod 72 which is adapted to cooperate with a pin 73 connected to escapement member 55. By depressing key 20" the escapement mechanism is operated to advance the carriage 48 one tooth space.

It is to be understood that the foregoing example is given for purposes of illustration only, and it is not intended that my claims shall be limited to the exact construction shown, for those skilled in the art will readily be able to modify the construction in many details without departing from the spirit of my invention.

What I claim is:

1. In a device for marking cards, means for holding a card, a carriage movable in relation to such means, a series of marking devices carried by said carriage adapted to punch holes in cards, a series of bars each operatively connected with one of the marking devices, a member adapted to rotate, comprising a series of rotating teeth, means for driving said member continuously, shoulders on each of said bars adapted to contact with said rotating teeth when drawn into contact therewith, a set of keys, mechanism connecting each key with one of said bars, and means whereby the shoulder on one of said bars will be drawn into operative relation with one set of said teeth when the corresponding key is depressed, so that said rotating member will cause the corresponding marking member to operate.

2. In a machine of the character described, the combination of a plurality of keys; a plurality of punches, one for each of a plurality of said keys; a carriage on which said punches are mounted; a constantly running prime-mover; means operable by said keys for causing said prime mover to effect operation of respective ones of said punches; and means operable as a concomitant to the operation of a punch, for effective step-by-step movement of said carriage.

3. In a machine of the character described, the combination of a carriage; a plurality of punches mounted on said carriage; a plurality of punch controlling keys, each correlated with a respective one of said punches; a constantly operating prime-mover for operating said punches under the control of said keys; means for causing step-by-step movement of said carriage upon operation of said keys; and a key and connections for effecting feeding of said carriage without effecting operation of any of said punches.

4. In a perforating machine comprising punches and pivotally and longitudinally movable operating bars for said punches, an

operating means for said bars, means on each of said bars for cooperative connection with said operating means, a projection on each of said bars, means normally bearing against each projection to prevent its bar from moving into cooperative relation with said operating means, pivoted members on said last stated means, and means on said projections and pivoted members for restoring each of said bars into its normal position as the bar is returned after a punching operation.

5. In the device for perforating a record card, the combination of means for holding the card, a series of punches, a carriage supporting said punches and mounted for movement relative to the card, a series of bars, a pair of bell cranks supporting each bar, a second series of bars supported by said bell cranks and operatively connected to said 10 punches and adapted when actuated to operate said punches, a shoulder on each of said first mentioned bars, a power driven cylindrical member adapted to be rotated continuously, a series of driving teeth on said member, a set of keys, mechanism connecting each key with one of the bars of the first series, means whereby the shoulder on one of said first mentioned bars will be brought into cooperative relation with the teeth of said rotating member when the corresponding key is 15 depressed, so that said rotating member will cause the corresponding punch to operate, and means operated during each punching operation for effecting relative movement between the card and said punches.

6. In a perforating machine the combination with means for supporting a card to be perforated, of a carriage movable step-by-step in front of said card, a series of punches mounted in said carriage, a series of operating bars mounted in the fixed framework of the machine and lying parallel with the travel of said carriage, one such bar for each punch, means for moving any selected one of said 20 bars transversely to its length and means whereby the corresponding punch will be actuated to perforate the card in whatever position the carriage may be at the time.

7. In a perforating machine comprising punches, a series of power driven operating bars, a step-by-step moving carriage, and means traveling with said carriage whereby any such bar when operated may actuate a punch to perforate a stationary card in whatever position said carriage may be at the time.

WILLIAM W. LASKER.
